LARS H. VOLD, OF WESTVILLE, NEW JERSEY, ASSIGNOR TO WILLIAM SELLERS & COMPANY, INCORPORATED, OF PHILADELPHIA, PENNSYLVANIA, A CORPORATION OF PENNSYLVANIA.

WORK-FEEDING MECHANISM.

1,080,793.

Specification of Letters Patent.

Patented Dec. 9, 1913.

Application filed May 1, 1913. Serial No. 764,768.

To all whom it may concern:

Be it known that I, LARS H. VOLD, a citizen of the United States, residing at Westville, county of Gloucester, and State of New Jersey, have invented a new and useful Improvement in Work-Feeding Mechanism, of which the following is a full, clear, and exact description, reference being had to the accompanying drawings, which form a part 10 of this specification.

In Patent No. 833,811 issued to me October 23, 1906, I have shown and described a punching machine, a work table adapted to travel back and forth through the punching machine, and grippers carried by the work-table and adapted to grip the work and pull it through the machine. In an application filed by me April 16, 1913, Serial No. 761,552 I have shown and described an apparatus 20 for automatically loading the work onto the work table and unloading it therefrom, adapted for use in connection with a punching machine or any other machine to which a loading and unloading apparatus could be of useful application.

The present invention is adapted for use in connection with a work-table such as is set forth in my said patent and application, although capable of being applied to a 30 traveling work-table of any construction.

It relates to the grippers for gripping the work and conveying it through a punching or other machine, and to mechanism associated therewith, and may be said to have 35 the following objects: 1. To support the work in a proper plane and yet permit it to move vertically under stress of the punches or other devices operating upon it. 2. To enable the grippers to be engaged quickly by 40 a single motion of a lever. 3. To enable the grippers to be released automatically and simultaneously. 4. To regulate, by ample means, the distance from the front of the work at which the first row of holes will be 45 punched by the machine.

The invention consists in the general and specific construction of the grippers and in the construction and arrangement of devices coöoperating therewith, whereby the above 50 mentioned objects are attained.

One preferred embodiment of the invention is shown in the accompanying drawings, in which—

Figure 1 is a side elevation, partly broken

away, of an apparatus embodying my invention. Fig. 2 is an enlarged detail view of a portion of one of the front grippers and actuating mechanism, in released position. Fig. 3 is a similar view of a portion of one of the rear grippers. Fig. 4 is a detail view 60 of one of the grippers in gripping position. Fig. 5 is an enlarged section on the line 5—5 of Fig. 1.

a is the machine, shown diagrammatically as a punching machine, which operates upon 65 the work.

The work-table comprises rack bars *b*, movable longitudinally on rollers *c*, and rollers *d* which directly support and guide the work. Rollers *c* and *d* are mounted on supports *e*. The rack-bars *b* are engaged by driving gears *f*, which are actuated from a suitable source of power. The rack-bars carry grippers which engage the work either at its front end, or at both ends. By 75 traversing the rack-bars *b* the grippers will travel with them and draw the work through the machine, say in the direction of the arrow, Fig. 1. After the punching operation, the grippers are released, the work is 80 removed, the rack-bars returned to their original position, and new work placed upon the work-table.

My present invention contemplates the employment of either a set of front grippers 85 only, or both a set of front grippers and a set of rear grippers. Both sets of grippers are similar in construction, although each embodies features of construction absent in the other. I have lettered the front grippers *g* and the rear grippers *h*. The front grippers are carried on a carriage comprising a cross-beam *i* mounted on carriers *j* secured to the rack-bars *b*. The rear grippers are carried on a carriage comprising a 90 cross-beam *k* secured to carriers *m* mounted on rollers *n* traveling on the rack-bars and which are therefore readily adjustable so that the grippers carried thereby may be positioned relatively to the front grippers in 95 100 accordance with the length of the work. It will be understood, therefore, that the force necessary to carry the work through the machine proceeds from the front grippers, the rear grippers coöperating to hold the 105 rear of the work in proper position and alinement.

I will first describe those features of con-

struction common to both sets of grippers and will then describe the features of construction peculiar to each set of grippers.

- Each gripper consists of a pair of pinching jaws, *o* and *p*, hinged together near the gripping point. The work is held by inserted hardened steel teeth *r*, preferably conical points or spuds. The lower jaw *o* is fulcrumed in a stand *s*, which is supported on the corresponding beam *i* or *k*, and adjustable thereon to accommodate the grippers to work of different width or of varying numbers of pieces. The stand *s* is shown as provided with a flat face abutting against the flat flange of the beam and lugs extending back of the beam, the lower lug abutting against the back of the said flange of the beam and the upper lug being spaced from said flange, but being held in fixed relation therewith by the screw *t*, which is tightened against the flange of the beam after the stand is adjusted to the desired position. The lower jaw *o* takes a solid abutment against the stand *s* back of the point 23 at which the jaw *o* is hinged, thus holding up the overhanging gripping end of the jaw and enabling it to form a good support for the work to which it is clamped. The inner end of the upper jaw *p* is forked and a block or bearing *u* is swiveled between the forks. An eye bolt *v* extends through the bearing *u*. The lower end of the eye-bolt *v* is connected by a pin *w* with a projection from a locking hand-lever *y*. Nuts *z* on the eye-bolt, on opposite sides of the bearing *u*, permit adjustment to suit variations in thickness of work, this being necessary because, as will be seen, the locking action is limited in stroke.
- The hand-lever *y* is mounted loosely on a short sleeve 10, which is keyed to the shaft 12 and turns in bearings in the stand *s*. The shaft 12 also turns in fixed bearings 24 attached to the cross beam *i* or cross beam *k*. The lever *y* is thus free to swing on the axis of the shaft. The lever cannot, however, swing to the right beyond the position shown in Fig. 4, the lever in this position bearing against a projection 11 on the sleeve 10, this projection acting as a stop to prevent the lever being thrown beyond the position it must occupy to move the upper jaw into gripping position. The shaft itself is prevented from turning in this direction by the stop 25, against which the levers 19 and 13 (hereinafter described) secured to the shaft, abut when the lever *y* and shaft 12 are in gripping position. It will be observed that when the lever is brought into this position, the center of the swiveling block *u*, the center of the pivot in eye bolt *v* and the center of shaft 12, are brought into practically a straight line, forming in effect a toggle joint, which tends to maintain the parts in gripping position. In the act

of punching there is a tendency on the part of the work to spring up. It is desirable, to avoid unnecessary strain on the gripping mechanism, that this tendency should have play. The construction described, in connection with the pivoting of the lower jaw, permits this, as, by reason of the location of swivel point 23 of the lower jaw substantially in line with the centers of the toggle-joint construction, a moderate upward movement of the work at the grip point can occur without seriously affecting the grip on the work.

It will be understood that when the work is brought into position between the jaws, each gripper is clamped to the work by a single motion of the lever *y*, the lever being moved from the position shown in Fig. 2 (or, in the case of the rear grippers, Fig. 3) to the position shown in Fig. 4, in which position it bears against the stop 11 on the sleeve 10 keyed to the shaft 12 as before described. The shaft cannot be turned to allow the projection 11 to move downward beyond the point shown in Fig. 4, but it can be turned in the opposite direction, thus forcing the projection 11 against the lever, unlocking the toggle and releasing the clamping pressure of the jaws upon the work.

To effect the automatic release of the rear grippers *h*, the shaft 12 coacting with these grippers and supported in bearings 24 on cross beams *i* or *k*, is provided at its end with a lever 13 (see Fig. 3). A pin 14 is placed on the frame of the punching machine in the path of the lever 13, which pin is so positioned that when the work reaches the point at which it is desired to release the grippers, the lever 13 strikes the pin 14 and is moved thereby into the position shown in Fig. 3, thereby turning the shaft and moving all the levers *y* sleeved thereon into position to release all the grippers, as above described. The rear carriage *k m* thereupon ceases to advance, the work being otherwise guided for the remainder of its travel. Means are also provided for automatically releasing the front grippers *g*. The front carriage *i j* being firmly bolted to the traversing rack-bars *b*, the distance it should move depends upon the length of the work to be punched. The releasing stop should therefore be adjustable. Such a stop 16 is shown in Figs. 1 and 2, adjustably secured to a longitudinally extending angle-bar 17. The stop is struck by a block 18 swinging on an arm 19 secured to the shaft 12. When the block 18 swings in the direction in which it is actuated by the stop 16, it abuts against the lower end of the arm 19 and the block and arm move together on the shaft's axis, thereby turning the shaft and releasing the front grippers. The stop 16 is set to clear block 18 throughout all the

length of punching. When punching is completed, the work is quickly traversed farther into the unloading position, at which point the stop 16 is placed. When the work is removed and the front grippers returned to be clamped to new work, the inclined rear face of the block strikes the stop and is swung thereby on its pivot so as to clear the stop without effecting any movement of the arm 19. It is not possible, therefore, for any breakage to occur on the reversal of the carriage *i j*.

After gripping the front edge of the work it is necessary to set it in the punching machine in the proper line for the first row of holes. It is desirable to accomplish this quickly and conveniently and without the necessity of measuring. This I do by the following simple means: Each of the front 20 grippers is provided with a stop shoulder 20 located directly back of the gripping point (see Fig. 4). The work is brought solidly against these shoulders before the grippers are closed. The shoulders on the various 25 front grippers are, of course, in the same line, so that when the work, either one piece or a number of pieces, is clamped, it will be square and true with the carriage *i j* and parallel with the line of punches. A distance-block 21 is bolted to one of the rock-bars *b* in front of the carriage *i j*. The distance block 21 is so positioned that if the rack-bars are moved rearwardly until the distance-block contacts with a fixed stationary abutment or projection 22 on the punching machine, the front edges of the plates or other work will be directly in the path of the centers of the row of punches. Therefore, if there be inserted between the abutment 22 and the distance block 21 a spacing-block (as indicated by the double-headed arrow *x*, Fig. 1) having a width equal to the distance from the edge of the work to the desired center line of the first row of holes, 40 and if the rack-bars *b* are moved back until the distance-block 21 abuts against the spacing-block and the latter abuts against the abutment 22, the work will necessarily be so located that the first row of holes will be punched exactly the right distance from the front edge.

Having now fully described my invention, what I claim and desire to protect by Letters Patent is:

1. In a machine of the character described, the combination with a longitudinally movable carriage, of a gripper comprising a pair of jaws extending in the direction of movement of the carriage and hinged together near their gripping points, the end of the lower jaw opposite the gripping end being hinged to the carriage and abutting against the same, back of its hinged support, thereby limiting the downward movement of the gripping end of the lower jaw and enabling

the gripping end of the jaw to properly support the work while permitting said gripping end to rise under stress, and manually actuated means, pivotally supported independently of the hinged support of the lower jaw, to move the upper jaw into and out of gripping relation to the lower jaw including means, coöperating with the hinged support of the lower jaw, permitting the gripping end of the upper jaw, when in gripping position, to rise, under stress, with the gripping end of the lower jaw.

2. In a machine of the character described, the combination with a longitudinally movable carriage, of a gripper comprising a pair of jaws extending in the direction of movement of the carriage and hinged together, a lever on the carriage mounted to turn on one transverse axis, one jaw being pivoted on another transverse axis and a member connecting the lever and the other jaw and turnable on transverse axes thereon and adapted, with the lever, to form a toggle joint, thereby, when the lever is turned to bring said axes in line, maintaining the second jaw in gripping position while permitting the gripping ends of both jaws to rise under stress of the work.

3. In a machine of the character described, the combination with a longitudinally movable carriage, of a gripper comprising a pair of jaws extending in the direction of movement of the carriage and hinged together near their gripping points, the end of the lower jaw opposite the gripping end being fulcrumed on one transverse axis on the carriage and abutting thereagainst, a lever on the carriage mounted to turn on another transverse axis, and a member connecting the lever and the end of the upper jaw opposite the gripping end and turnable on transverse axes on said lever and upper jaw and adapted with the lever to form a toggle joint.

4. In a machine of the character described, the combination with a longitudinally movable carriage, of a gripper comprising a pair of jaws hinged together near their gripping points, a lever on the carriage mounted to turn on a transverse axis, a block swiveled on the end of one jaw opposite the gripping end, a bolt secured to said block, a pin connecting the bolt with the lever, and a stop fixed relatively to the shaft and limiting the movement of the lever when the same is moved to bring the center of the swiveling block, the axis of the pin and the axis of the lever into alinement.

5. In a machine of the character described, the combination with a longitudinally movable carriage, of a stand transversely adjustable on the carriage, a pair of jaws extending in the direction of movement of the carriage and hinged together, the end of the lower jaw opposite the grip-

ping end hinged to the stand on one transverse axis and abutting against the stand back of its hinged connection therewith to afford a support for the work, a lever turnable on another axis extending transversely through the stand, and a member connecting the lever and the end of the upper jaw opposite the gripping end and turnable on transverse axes on said lever and jaw and adapted with the lever to form a toggle joint.

6. In a machine of the character described, the combination with a longitudinally movable carriage, of a stand transversely adjustable on the carriage, a pair of jaws hinged together, a shaft extending transversely through the stand, a lever loosely sleeved on the shaft, connections between the lever and one of the jaws adapted to be operated by the lever to move the jaw into gripping position, and a stop on the shaft limiting the movement of the lever in one direction and adapted when the shaft is turned in the opposite direction to retract the lever and thereby through said connections release the grip of said jaw.

7. In a machine of the character described, the combination with a longitudinally movable carriage, of a stand transversely adjustable on the carriage, a pair of jaws hinged together, a shaft extending transversely through the stand, a lever loosely sleeved on the shaft, a bolt connecting the lever and one of said jaws and turnable on transverse axes thereon and adapted, with the lever, to form a toggle joint, a stop turning with the shaft adapted to engage the lever adjacent to the pivot of the bolt thereon and limit the movement of the lever after the same has been turned to bring said axes and the center of the shaft into alinement, and means adapted to turn the shaft and thereby cause the stop to retract the lever and unlock the toggle and thereby release the grip of the jaw.

8. In a machine of the character described, the combination with a longitudinally movable carriage, of a stand transversely adjustable on the carriage, a shaft extending transversely through the stand, a lever loosely sleeved on the shaft, a pair of jaws hinged together near their gripping points, the end of the lower jaw opposite the gripping end extending under the stand and abutting against the same to afford a support for the work, a block swiveled on the end of the upper jaw opposite the gripping end, a bolt secured to said block, a pin connecting the bolt with the lever, a stop turning with the shaft and adapted to engage the lever adjacent to said pin and limit the movement of the lever after the same has been turned to bring the center of the swiveling block, the center of the pin and the center of the shaft into alinement, and means to turn the shaft and thereby cause the stop to retract the lever and unlock the toggle and thereby

cause the gripping end of the upper jaw to recede from the gripping end of the lower jaw.

9. In a machine of the character described, the combination with a longitudinally movable carriage, of a plurality of grippers on the carriage, devices to actuate the respective grippers to cause them to grip the work, a shaft carried by the carriage, means turning with the shaft adapted when the shaft is turned in one direction to simultaneously actuate said devices to cause the grippers to release the work, a stop stationary relative to the carriage, and an arm on the shaft adapted to be actuated by the stop to so turn the shaft.

10. In a machine of the character described, the combination with a longitudinally movable carriage, of a gripper comprising a pair of jaws extending in the direction of movement of the carriage and hinged together, a toggle joint connected at one end with one jaw and pivoted at the other end on the carriage, the other jaw being pivoted on the carriage on an axis different from the axis on the carriage on which the last named end of the toggle joint is pivoted, and means to move the toggle into its extended position thereby causing the first jaw to swing into gripping relation with the other jaw.

11. In a machine of the character described, the combination with a longitudinally movable carriage, of a lower gripping jaw extending in the direction of the movement of the carriage and at its rear end portion pivotally supported on the carriage, an upper gripping jaw pivoted near its front end to the lower jaw, a transverse shaft on the carriage above the pivotal support of the lower jaw, the rear end portion of the upper jaw extending above the shaft and a toggle joint connection between the shaft and the rear end portion of the upper jaw, the pivot of the lower jaw and the points of connection between the toggle and the shaft and the upper jaw being substantially in line, thereby permitting the gripping ends of the jaws, when in gripping position, to rise under stress without affecting the grip of the jaws upon the work.

12. In a machine of the character described, the combination with a carriage, of a series of grippers each comprising a pair of jaws hinged together, a toggle joint connected with one jaw of each pair, means including hand operated levers, to move each toggle independently into and out of its extended position, and means independent of said levers to simultaneously move all the toggles out of their extended positions thereby opening the jaws of all the grippers.

13. In a machine of the character described, the combination with a carriage, of a gripper comprising a pair of jaws hinged

5 together, a transversely extending shaft moving with the carriage, a toggle joint connected with one jaw, the two members of the toggle pivoted on said shaft and jaw respectively, manually operable means to move the toggle into its extended position thereby causing said jaw to swing into gripping relation with the other jaw, and means turning with the shaft adapted to move the toggle 10 out of its extended position thereby moving the first-named jaw out of operative relation with the other jaw.

14. In a machine of the character described, the combination with a longitudinally movable carriage, of a gripper comprising a pair of jaws hinged together, a transversely extending shaft moving with the carriage, a toggle joint connected with one jaw, the two members of the toggle turning on axes on said shaft and jaw respectively, means to move the toggle into its extended position thereby causing said jaw to swing into gripping relation with the other jaw, a stop on the shaft adapted to engage the toggle and limit its movement beyond such extended position and adapted when the shaft is turned in the opposite direction to unlock the toggle and retract said jaw.

15. In a machine of the character described, the combination with a carriage, of a gripper comprising a pair of jaws hinged together, a transversely extending shaft movable with the carriage, a lever pivoted on the shaft, a member pivotally connected with both the lever and one of the jaws, said lever and member together forming a toggle adapted, by operating the lever, to be moved into its extended position and thereby swing said jaw into gripping relation with the other jaw, and means turning with the shaft adapted to move the toggle and lever into position to swing the first-named jaw out of gripping relation with the other jaw.

16. In a machine of the character described, the combination with a carriage, of a gripper comprising a pair of jaws hinged together, a transversely extending shaft movable with the carriage, a lever pivoted on the shaft, a member pivotally connected with both the lever and one of the jaws, said lever and member together forming a toggle adapted, by operating the lever, to be moved into its extended position and thereby swing said jaw into gripping relation with the other jaw, a stop on the shaft adapted to prevent the movement of the toggle beyond its extended locking position, and means to turn the shaft to cause said stop to unlock the toggle and thereby swing the first named jaw out of gripping relation with the other jaw and retract the lever into its unlocking position.

17. In a machine of the character described, the combination with a longitudi-

nally movable carriage, of a gripper comprising a pair of jaws hinged together, a transversely extending shaft moving with the carriage, a toggle joint connected with one jaw, the two members of the toggle 70 turning on axes on said shaft and jaw respectively, means to move the toggle into its extended position thereby causing said jaw to swing into gripping relation with the other jaw, a stop stationary relative to the 75 carriage, an arm on the shaft adapted to be actuated by the stop to turn the shaft, and means carried by the shaft adapted, when the shaft is so turned, to unlock the toggle and release said jaw.

18. In a machine of the character described, the combination with a longitudinally movable carriage, of a transversely extending shaft carried by said carriage, a plurality of stands adjustable transversely 85 of said carriage and through which said shaft extends, grippers, one for each stand, each gripper comprising a pair of jaws hinged together, levers, one for each gripper, turning loosely on the shaft, a bolt pivoted on each lever and on one jaw of the corresponding lever and forming with the lever a toggle joint, stops on the shaft, one adapted to engage each lever and limit its movement in one direction and adapted 95 when the shaft is turned in the opposite direction to move the lever and unlock the toggle, a stop stationary relative to the carriage, and an arm on the shaft adapted to be actuated by the last named stop to turn 100 the shaft and thereby cause the first named stops to simultaneously unlock all the toggles.

19. In a machine of the character described, the combination with a longitudinally movable carriage, of a plurality of grippers on the carriage, devices to actuate the respective grippers to cause them to grip the work, a shaft carried by the carriage, means turning with the shaft adapted when 105 the shaft is turned in one direction to simultaneously actuate said devices to cause the grippers to release the work, a stop stationary relative to the carriage, an arm on the shaft, and a block pivoted on and adapted to abut against the arm and engage the stop in the travel of the carriage, thereby causing the arm to be moved to so turn the shaft.

20. In a machine of the character described, the combination with a longitudinally movable carriage, of a plurality of grippers on the carriage, devices to actuate the respective grippers to cause them to grip the work, a shaft carried by the carriage, means turning with the shaft adapted when the shaft is turned in one direction to simultaneously actuate said devices to cause the grippers to release the work, a stop stationary relative to the carriage, an arm on 120 125 130

the shaft, a block pivoted on and adapted to abut against the arm and engage the stop in the travel of the carriage in one direction, thereby causing the arm to be moved 5 to so turn the shaft, said block having an inclined face adapted, in the movement of the carriage in the opposite direction, to engage the stop and cause said block to turn on its axis and thereby override the stop 10 without imparting movement to the shaft.

21. In an apparatus of the character described, the combination with a longitudinally movable carriage, of grippers on the carriage adapted to engage and traverse the 15 work, means limiting the forward movement of the work relatively to the grippers, a distance block fixed relative to the carriage, a machine for operating upon the

work, and an abutment fixed relatively to the machine, and adapted to be engaged by 20 said distance block when the carriage is moved forward, thus bringing the forward edge of the work in a predetermined position relatively to the machine, thereby enabling a spacing block to be inserted between 25 said distance block and abutment to determine the distance from the forward edge of the work at which operations upon the work shall begin.

In testimony of which invention, I have 30 hereunto set my hand, at Philadelphia, on this 29th day of April, 1913.

LARS H. VOLD.
